UNITED STATES PATENT OFFICE.

ELLA T. GREELEY, OF WHITMAN, MASSACHUSETTS.

DESIGN FOR A RADIATOR ORNAMENT.

Application filed July 30, 1928. Serial No. 27,624. Term of patent 3½ years

To all whom it may concern:

Be it known that I, ELLA T. GREELEY, a citizen of the United States, residing at Whitman, in the county of Plymouth and State of Massachusetts, have invented a new, original, and ornamental Design for Radiator Ornament, of which the following is a specification, reference being had to the accompanying drawing, forming part thereof.

The figure is a front elevation of a radiator ornament showing my new design.

I claim:

The ornamental design for a radiator ornament, as shown.

ELLA T. GREELEY.
